(57) **CLAIM**

The ornamental design for a fascia gun, as shown and described.

DESCRIPTION

FIG. 1 is a front perspective view of a fascia gun showing the claimed design;

FIG. 2 is a bottom perspective view seen from a bottom side thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a partial enlarged view of the part as designated by label 9 in FIG. 1; and,

FIG. 10 is another partial enlarged view of the part as designated by label 10 in FIG. 1.

The broken lines immediately adjacent to the claimed portions as shown in the drawings represent the boundaries of the claimed design and form no part thereof. The unevenly spaced dot-dashed broken lines in FIGS. 1, 9, and 10 depict boundaries of the enlarged figures and form no part of the claimed design.
